US00D757114S

(12) United States Design Patent
Lee et al.

(10) Patent No.: US D757,114 S
(45) Date of Patent:  May 24, 2016

(54) DISPLAY SCREEN OR PORTION THEREOF
WITH ICON

(71) Applicant: Samsung Electronics Co., Ltd.,
Suwon-si (KR)

(72) Inventors: Seung-Myung Lee, Seoul (KR);
Jin-Hee Kwon, Seoul (KR)

(73) Assignee: Samsung Electronics Co., Ltd.,
Suwon-si (KR)

() Term: 14 Years

(21) Appl. No.: 29/486,971

(22) Filed: Apr. 4, 2014

(30) Foreign Application Priority Data

Feb. 21, 2014 (KR) 30-2014-0008970

(51) LOC (10) Cl. 14-04
(52) U.S. Cl.

USPC D14/495

(58) Field of Classification Search

USPC D14/485, 486, 487, 488, 489, 490, 491,
D14/492, 493, 494, 495; D18/26, 31, 32, 33

CPC G06F 3/04817

(57) CLAIM

We claim the ornamental design for a display screen or portion thereof with icon, as shown and described.

DESCRIPTION

FIG. 1 is a front view of a display screen or portion thereof with icon showing our new design;

FIG. 2 is a second embodiment thereof; and,

FIG. 3 is a third embodiment thereof.

The long dash, short dash broken lines represent the display screen or portion thereof and form no part of the claimed design.

1 Claim, 3 Drawing Sheets
